UNITED STATES PATENT OFFICE.

RALPH E. FERRIS, OF SWISSVALE, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,227,413.

Specification of Letters Patent. Patented May 22, 1917.

Application filed April 4, 1914. Serial No. 829,427.

To all whom it may concern:

Be it known that I, RALPH E. FERRIS, a citizen of the United States, and a resident of Swissvale, in the county of Allegheny and State of Pennsylvania, have invented 5 a new and useful Improvement in Systems of Control, of which the following is a specification.

My invention relates to systems of control for electric motors, and it has special 10 reference to means for supplying a suitably low, and approximately constant, voltage to a receiving circuit, such, for example, as the control or lighting circuit of an electric 15 railway train, from a plurality of supply circuits of materially different voltages.

One of the objects of my invention is to provide an apparatus of the motor-generator type that is adapted to be operated 20 from any one of a plurality of supply circuits of materially different voltages, while maintaining a substantially constant voltage delivered from the generator.

Another object of my invention is to provide, 25 in a system of the above-indicated character, means for maintaining a substantially constant voltage in the receiving circuit throughout relatively wide and sudden changes in the load conditions on the electric motors.

Another object of my invention is to provide an apparatus of this general class which shall be compact and durable in construction and flexible and reliable in operation. 35

In modern interurban direct-current railway systems, it is often found desirable and necessary, for various operating reasons, to supply various portions of the transmission 40 systems or supply circuits with voltages of materially different values, for instance, 600 volts when operating in or near city properties, and 1200 volts when running on the interurban portions of the lines. It appears 45 probable that in the near future even higher direct-current voltages will be employed, and it is my aim in the present invention to provide suitable and desirable means for meeting one of the new problems encountered in this new field.

According to my invention, I provide, 50 preferably, a plurality of mechanically associated electric motors of the series type, collectively driving a generator for supplying the auxiliary circuits, a fluid-compress-

ing apparatus, such as is customarily employed in connection with braking systems and for other purposes, and a blower for use in cooling the propelling motors during operation. The generator and the 60 blower are preferably driven continuously by the series-type motors, thereby preventing an excessive running speed thereof. The compressing apparatus is preferably automatically connected to the driving 65 motors at intervals that are dependent upon the degree of air pressure in the system. The load variations, thus intermittently imposed upon the motors, have the effect of changing their speed and, consequently, the 70 delivered voltage of the mechanically associated generator, unless some suitable counteracting means is provided. Accordingly, the system of the present invention comprises various means for varying the field 75 excitation of the driving motors to maintain a substantially constant speed thereof or for varying the field excitation of the generator, thereby tending to supply a substantially constant voltage to the receiving 80 circuit. In addition, a suitable switching means is provided for properly connecting the motors to any one of the supply circuits, as occasion may require. For example, if each motor armature winding is 85 inherently adapted for operation at 600 volts, and if four such windings are employed, then, by parallel, series-parallel and series-circuit arrangements of the windings, the apparatus may be readily operated at 90 600, 1200 and 2400 volts, respectively, while maintaining substantially uniform operating characteristics of the generator.

In the accompanying drawing, Figure 1 is a plan view of an apparatus constructed 95 in accordance with my invention, Fig. 2 is a diagrammatic view of a control system embodying the apparatus shown in Fig. 1, and Figs. 3 and 4 are diagrammatic views of modifications of the control system illustrated in Fig. 2.

Referring to Fig. 1 of the drawing, the apparatus here shown comprises a plurality of electric motors 1 and 2, preferably of the double commutator type, severally provided with a plurality of armature windings, (not shown) that are severally connected to commutator cylinders 3, 4, 5 and 6; a generator 7, of any suitable type, that is mechanically associated with the arma- 110

tures of the motors 1 and 2 by means of a suitable gear train 8, or in any other suitable manner, a fluid-compressing apparatus 9, of any suitable type, that is adapted for 5 intermittent mechanical connection with the driving motors 1 and 2 through the agency of a geared clutch 10 and a counter shaft 11, which is driven directly by gears on the shafts of the motors; and a blower 12 10 of any familiar type.

The clutch 10 may be of any well-known class, and is preferably of the type set forth in connection with the system shown in my co-pending application, Serial No. 15 809,635, filed December 31st, 1913.

Reference may now be had to Fig. 2 wherein the control system shown comprises a plurality of supply circuits, such as trolley conductors V, 2V and 4V that are provided 20 with a common return conductor marked "Ground". The electric motors 1 and 2 are diagrammatically represented by the commutator cylinders 3 to 6, inclusive, and a plurality of corresponding subdivided series field windings 13. The generator 7 is provided with a variable shunt field winding 14, and a receiving circuit 15, such as the control and lighting circuits of an electric railway system, is connected across the 25 terminals of the generator. A suitable switching device 16 is mechanically associated with the clutch 10 for simultaneously short circuiting a portion of each the motor series field windings 13, by means of a plurality of magnet switches 13^a, the energizing coils of which are adapted to be excited by a battery SB, for a purpose to be hereinafter specified.

The voltages of the supply circuits 2V and 40 4V are preferably multiples of the voltage of the supply circuit V, as indicated by the reference characters applied to them. Switches 17 are provided for connecting the driving motors to the circuits V, 2V and 4V 45 in series, series-parallel and series-circuit relation, respectively, according to the relative positions of the switches. For the sake of clearness, the circuits for connecting the motors in series relation across the supply 50 circuit 4V are indicated in heavy solid lines, the control circuits supplied from the circuit 2V are indicated in light lines and the control circuits connected to the supply circuit V are indicated in dotted lines. The 55 operation may be described as follows: Assuming that each of the motor armature windings is inherently adapted for operation from a supply circuit of V volts, then, by suitable manipulation of the switches 17, 60 the armature windings may be connected to any one of the three supply circuits shown and, in any case, will operate at a substantially constant speed. The speed and, consequently, the voltage of the mechanically 65 associated generator 7 will, therefore, remain

substantially the same, irrespective of which supply circuit the motors are operated from. When the fluid-compressing apparatus is not in operation, a certain relatively low motor current and motor speed will obtain; and, 70 when the apparatus is connected to the motors by the actuation of the clutch 10, as more specifically set forth in my co-pending application, hereinbefore identified, a pre-determined increase in load will be imposed 75 upon the series motors, and the speed thereof will, consequently, tend to decrease. However, upon the actuation of the clutch 10, the switch 16 is closed to cause the short-circuiting of a portion of each of the motor 80 series field windings 13, by reason of the energization of the coils of the magnet switches 13^a, thereby weakening the field flux and causing the motors to increase their speed. By suitable design of the field wind- 85 ings 13, the speed and voltage of the driven generator 7 may be maintained substantially constant throughout the variations of load referred to.

In Figs. 3 and 4, for the sake of clearness 90 and simplicity, the series-parallel switching means illustrated in connection with the motors in Fig. 2 have been omitted; it will be understood, however, that the operation of the motors is the same as described in 95 connection with Fig. 2.

In Fig. 3 a series-type field winding 18 for the generator armature 7 is shown as connected in series relation with the motor series field windings 19. By suitably designing and 100 proportioning the field windings 18 and 19 with respect to the magnetic circuits of the corresponding armatures, or, in other words, by designing the motors and the generator to have the same magnetization curve or 105 magnetic saturation properties, the voltage delivered to the receiving circuit 15 by the generator may be maintained substantially constant, inasmuch as a decrease of the speed of all the machines by reason of an increased 110 motor load, such as the connection of the fluid-compressing apparatus, is substantially compensated for by the increased current traversing the generator field winding 18, and vice versa, whereby the flux traversing 115 the generator armature 7 varies practically inversely as the armature speed, and the resultant voltage remains substantially constant.

In Fig. 4, in addition to the circuits illustrated in Fig. 3, a separately excited field winding circuit 20 for the driving motors is provided and is connected across the terminals of the generator 7. It will be understood that, by reason of the shunt characteristic thus 120 supplied to the motors, a mechanical load for preventing an excessive motor speed is unnecessary. The operation of this system may be briefly described as follows: Upon the connection of the fluid-compressing ap- 125 130

paratus 9 to the driving motors, the tendency to decrease the motor speed tends also to reduce the voltage of the generator. Consequently, the current in the motor shunt 5 field circuit 20 is reduced, thereby causing an increase in motor speed, in accordance with well known principles. By a proper design of parts, the speed of the motors may thus be maintained substantially constant, with the result that the voltage of the 10 receiving circuit 15 is also kept substantially the same.

I do not wish to be restricted to the specific structural details and circuit connections herein set forth for illustrative purposes, but desire that only such limitations shall be imposed as are indicated in the appended claims.

I claim as my invention:

20 1. A control system comprising a supply circuit, a plurality of mechanically associated dynamo-electric machines fed therefrom, means for varying the load upon said machines by a predetermined amount, another dynamo-electric machine driven by 25 said first machines, and means for maintaining the voltage of said last machine substantially constant, as the said load varies.

2. A control system, comprising a supply 30 circuit, a plurality of mechanically associated driving dynamo-electric machines fed therefrom, a driven apparatus adapted to vary the load upon said machines by a predetermined amount, a generating dynamo-electric machine driven by said first machines, and means dependent upon the load 35 variations for varying the electrical conditions in said generating machine to maintain the voltage thereof substantially constant, as the said load varies.

3. A control system comprising a supply 40 circuit, a plurality of mechanically associated electric motors connected in series-relation across said circuit, a fluid compressing apparatus adapted to be mechanically 45 connected to said motors, a generator driven by said motors, and switching means dependent upon the mechanical connection and disconnection of said apparatus for varying the exciting field current of said generator 50 to maintain the voltage thereof substantially constant, as the load varies.

4. In a control system, the combination 55 with a supply circuit of relatively high voltage, of a plurality of mechanically associated dynamo-electric machines fed therefrom, means for varying the load upon said machines by a predetermined amount, another dynamo-electric machine driven by 60 said first machines, a receiving circuit of relatively low voltage connected to said last machine, and means for maintaining the voltage of said receiving circuit substantially constant, as the said load varies.

5. In a control system, the combination 65 with a supply circuit of relatively high voltage, of a plurality of mechanically associated driving dynamo-electric machines fed therefrom, a driven apparatus adapted to vary the load upon said machines by a predetermined amount, a generating dynamo-electric machine driven by said first machines, a receiving circuit of relatively low voltage connected across said last machine, and means dependent upon the load variations for varying the electrical conditions in said generating machine to maintain the voltage thereof substantially constant, as the said load varies.

6. In a control system, the combination 70 with a supply circuit of relatively high voltage, of a plurality of mechanically associated electric motors connected in series relation across said circuit, a fluid-compressing apparatus adapted to be mechanically 75 connected to said motors, a generator driven by said motors, a receiving circuit of relatively low voltage connected across said generator, and switching means dependent upon the mechanical connection and disconnection of said apparatus for varying the exciting field current of said generator to maintain the voltage thereof substantially constant, as the load varies.

7. A control system comprising a plurality 80 of supply circuits of materially different voltages, a plurality of mechanically associated driving dynamo-electric machines, means for connecting said machines in proper relative circuit relation to any of 85 said supply circuits, a driven apparatus adapted to vary the load upon said machines by a predetermined amount, a generating dynamo-electric machine driven by 90 said first machines, and means dependent upon the load variations for varying the electrical conditions in said generating machine to maintain the voltage thereof substantially constant, as the said load varies.

8. A control system comprising a plurality 95 of supply circuits of materially different voltages, the higher voltages being substantial multiples of the lowest voltage, a plurality of mechanically associated electric motors severally inherently adapted for 100 operation from said lowest voltage, means for connecting said machines in parallel circuit relation across the supply circuit of lowest voltage, in series-parallel circuit relation across the supply circuit of next 105 higher voltage, and in series-circuit relation across the circuit of highest voltage, a fluid compressing apparatus adapted to be mechanically connected to said motors, a generator driven by 110 said motors, and switching means dependent upon the mechanical connection and disconnection of said apparatus for varying the exciting field current,

- of said generator to maintain the voltage thereof substantially constant, as the load varies.
9. A control system comprising a supply circuit, a plurality of mechanically associated driving dynamo-electric machines severally having series field windings divided into sections, a driven apparatus adapted to vary the load upon said machines by a predetermined amount, and a generating dynamo-electric machine driven by said driving machines, of means for varying the active portions of said driving dynamo-electric machine field windings in accordance with the load on said driving machines.
10. In a control system, the combination with a supply circuit, a plurality of mechanically associated electric motors severally having series field windings divided into sections, a fluid-compressing apparatus adapted to be mechanically connected to said motors, a generator driven by said motors, and a receiving circuit of relatively low voltage connected across said generator, of means for varying the active portions of said motor field windings in accordance with the load on said motors to maintain the speed thereof substantially constant.
11. A control system comprising a supply circuit, a plurality of mechanically as-
- sociated electric motors fed therefrom, means for varying the load upon said machines by a predetermined amount, a generating machine driven by said motors, and means dependent upon the load variations for varying the field excitation of said motors to maintain substantially constant speed thereof, whereby the generating machine voltage remains substantially constant, as the load varies.
12. A control system comprising a supply circuit, a plurality of mechanically associated electric motors fed therefrom, a fluid-compressing apparatus adapted to be mechanically connected to said motors, a generator driven by said motors, and switching means dependent upon the mechanical connection and disconnection of said apparatus for varying the active portions of the motor field windings to maintain substantially constant speed of the motors, whereby the generating machine voltage remains substantially constant, as the load varies.
- In testimony whereof, I have hereunto subscribed my name this 25th day of Mar. 1914.

RALPH E. FERRIS.
